DESIGN FOR A FRUIT PRESS

Joseph M. Majewski, Jr., Kansas City, Mo., assignor to Foster L. Talge, Kansas City, Mo., doing business as the Rival Manufacturing Company

Application June 5, 1937, Serial No. 69,681

Term of patent 14 years

To all whom it may concern:

Be it known that I, Joseph M. Majewski, Jr., residing at Kansas City, in the county of Jackson and State of Missouri, have invented a new, original, and ornamental Design for a Fruit Press, of which the following is a specification, reference being had to the accompanying drawing, forming part thereof, in which

I claim:

The ornamental design for a fruit press substantially as shown.
